PAPER-FEEDING MECHANISM.

1,403,250.

Specification of Letters Patent. Patented Jan. 10, 1922.

Application filed December 16, 1918. Serial No. 267,027.

To all whom it may concern:

Be it known that we, ARCHER G. JONES and ALBERT W. NIELSON, both citizens of the United States, residing at Richmond, in the county of Henrico and State of Virginia, have invented a new and useful Improvement in a Paper-Feeding Mechanism, of which the following, together with the accompanying drawings, is a specification.

10 The present invention relates to mechanism for feeding sheets or articles of paper, and in particular, contemplates certain improvements in the feeding instrumentalities of a rotary printing press, designed for operation on successively presented sheets or articles.

The invention is herein shown as applied to the feeding of envelopes or like articles to a rotary printing press of standard construction, of which certain parts are shown that are essential to a clear understanding of the present invention. It is to be understood, however, that the invention is not in any sense limited or confined in its application to 25 the type of press herein shown or described, but is susceptible of adaptation to various other types of presses, for the rapid, accurate and economical feeding of various other classes of goods.

30 The invention embodies marked improvements and advantages over the known types of feeding mechanisms now in use on presses of this class, said improvements and advantages being fully set forth in the detailed description that follows, and being shown in the accompanying drawings, wherein Figure 1 is a longitudinal sectional view of the essential elements of the invention, shown in operative relation to the impression and type carrying cylinders of a rotary press.

Figure 2 is a transverse view of the mechanism, certain parts being removed in order to show the cooperation of the mechanism with the throw-off devices of the press.

45 Figure 3 is a fragmentary view of the parts appearing in the lower portion of Fig. 1, certain of said parts being removed to disclose other parts more clearly.

50 Figure 4 is a longitudinal sectional view through the parts of a valve mechanism constituting part of the invention.

Figure 5 is a face view of a rotating valve member, from the plane of the line 5—5, Fig. 4.

Figure 6 is a sectional view, on the line 55 6—6, Fig. 2.

Figure 7 is a fragmentary plan view, of mechanism seen from the top of Fig. 1.

Like reference characters refer to like parts in the different figures.

The present invention is shown as applied to a rotary printing press, the essential elements of which are conventionally indicated in the drawing as a type carrying cylinder 1, and an impression cylinder 2, said cylinders being journalled between side frames 3, 3. As is usual in presses of this class, and as for instance shown in United States Letters Patent No. 577,405 and No. 661,245, issued February 16, 1897 and November 6, 1900, respectively, jointly to Charles G. Harris and John F. McNutt, provision is made for the separation of these normally cooperating cylinders 1 and 2 in the absence of a sheet or other article between them, so as to prevent the contact of the type on cylinder 1 with the surface of cylinder 2. To this end, as in the machines of the aforesaid patents to Harris and McNutt, the shaft of cylinder 2 is mounted in eccentrics 4, which are journalled in the frames 3, 3, in such manner that when arms 5, 5, of said eccentrics are raised, the shaft of cylinder 2 is lowered.

To control the action of these eccentrics, 85 the arms 5, 5, are connected at their outer ends to rods 6, 6, which latter are pivoted at their lower ends to cranks 7, 7, secured to a spring held shaft 8 that is journalled in the frames 3, 3. To throw the impression cylinder 2 to its highest point, so that stock thereon will receive the impression of the type forms of cylinder 1, the shaft 8 is turned, against the tension of its springs 9, by means of a handle 10, until a shoulder 11 of a collar 12, fast on said shaft, is engaged by the hooked end of an arm 13. This arm 13 is journalled loosely on a shaft 14 that is oscillated by any suitable means, not shown, for the purpose of securing the alternate separation and bringing together of pairs of feed rolls 15, 15, adapted to receive the stock and forward it to the cylinders 1 and 2.

As in the aforesaid patents to Harris and McNutt, the arm 13 is here shown as provided with a laterally projecting lug 16. Adjacent to the arm 13 and fast on the oscillating shaft 14 is an arm 17, Fig. 6, which

carries at its lower end a lug or block 18, that is overhung by the lug 16 of arm 13. The relation of the arms 13 and 17 is such that if there being nothing interposed between the lugs 16 and 18, the arm 17 will not, in the partial rotation of shaft 14, in any way act upon the arm 13, and consequently the hooked end of the latter will remain in engagement with the collar 12, thus retaining 10 the impression cylinder controlling shaft 8 in its operative position.

As in the aforesaid patents to Harris and McNutt, the above described mechanism is made responsive to the presence or absence 15 of stock between the feed rolls 15, 15, for controlling the tripping of shaft 8. To this end, a feeler-lever 19 is disposed between said feed rolls 15, said lever being fulcrumed on a bracket 20 that is carried by one of the 20 standards 21 employed in the intermittent movement of said feed rolls. The other arm of lever 19 has a pin and slot engagement with a lever 22, which is fulcrumed, by means of a slot 23 on a screw 24. At its 25 lower end the lever 22 carries a lug 25, which is designed during the proper operation of the press to be intermittently moved into and out of the space between the lugs 16 and 18. The upper arm of lever 19 is free 30 to move into an annular groove or space provided between portions of the upper feed roll 15, in the absence of stock between the feed rolls 15.

When stock is properly fed between the 35 upper and lower feed rolls 15 this upper arm of the feeler-lever 19, by the elevation of standard 21, is depressed upon coming in contact with the stock between the feed rolls, thus causing the actuation of lever 22. The 40 rocking of lever 22 throws the lug 25 out of the space between lugs 16 and 18. This prevents the swinging arm 17 from having any effect upon the hooked arm 13. If however, there be no stock between the feed rolls 45 15 when they are brought into contact by elevation of standard 21, then the upper arm of the feeler-lever 19 will pass into the groove or space of upper feed roll 15 when acting upon the lever 22. The lug 25 being 50 within the space between lugs 16 and 18 when the arm 17 is moved upward, it will effect the upward movement of arm 13 and its disengagement with collar 12, thus permitting the spring impelled shaft 8 to bring 55 about the lowering of impression cylinder 2. When the lever 22 is thus not actuated by the feeler-lever 19, it is free to be moved upward under the action of arm 17 by sliding on its fulcrum screw 24.

60 Of itself, the mechanism above described is not new, but is well known in presses of the type disclosed in the aforesaid patents to Harris and McNutt. According to the present invention, said mechanism above described is combined and co-related with a

novel and highly efficient feeding mechanism for advancing stock between the rolls 15, 15, in such a manner that the operation thereof is greatly improved. Said feeding mechanism, for delivering the stock between 70 the feed rolls 15, 15, will now be described in detail.

As herein shown by way of example, the stock to be fed consists of a stack 26 of envelopes or similar articles, said stack being 75 confined and supported in a plurality of guide bars 27, 27, that extend upwardly and rearwardly from a supporting block 28. According to the invention, envelopes or other articles are withdrawn one by one 80 from the bottom of the stack, and are deposited thereafter on a feed table 29, from which they are pushed or otherwise delivered into the space between the feed rollers 15. The lowermost article of the stack 85 26 has its opposite edges engaged by two or more small rollers, 30, which are freely journaled on pins carried by the block 28, so that the peripheries of said rollers project inwardly slightly beneath and in supporting relation to said edges of the lowermost article. As said article is withdrawn, by a tensile pull exerted on its under surface, as hereinafter described, it is flexed slightly to draw it past the contacting rollers 30, which are free to rotate under the friction of the article against their peripheries. The article next above then descends by gravity into contact with said rollers 30, which support the same and the superposed 90 stack as before, until the withdrawing means again becomes operative.

As herein shown, said withdrawing means consists of a plurality of suction tubes 31, here shown as four in number, which project 105 upwardly from a hollow block 32. The block 32 is carried on the free end of an arm 33 which is journaled on a rod 34 that extends transversely between the side frames 3, 3. The arm 33 has a projecting lug 35 on its 110 under side, to which is pivotally connected a link or rod 36, whose lower end is forked, as at 37 to embrace a shaft 38. The link or rod 36 has journalized thereon a cam roller 39 which is adapted to travel in the cam groove 115 40 of a cam 41 on shaft 38. The shaft 38 is constantly rotated, during the operation of the machine through a suitable connection, such as a sprocket chain 42, with the shaft of the constantly rotating impression cylinder 2. Through the link 36, therefore, a rocking movement is imparted to the arm 33 to raise the block 32 and suction tubes 31 from the full line position to the dotted line position shown in Fig. 1, thus bringing said 125 suction tubes into contact with the lowermost article of stack 26, and then lowering said suction tubes to cause the deposit of the seized article on the feed table 29.

The hollow interior of block 32, with 130

which the suction tubes 31 communicate, has a flexible connecting tube or pipe 43 that leads to the interior of a member 44, Fig. 4, having a tubular passage 45 therein. A second member 46 having an aligned tubular passage 47 is disposed opposite the member 44, and said tubular passage 47 has leading therefrom a flexible connector 48 that leads to a suitable exhausting mechanism, such as 10 a vacuum pump, not shown. The members 44 and 46 are each loosely disposed on oppositely projecting hub portions 49, 49, of a disk 50 that is pinned or keyed to the shaft 38 and interposed between said two members. 15 Interposed between the disk 50 and the member 46, and also loosely disposed on the corresponding hub portion 49 is a disk 51 having an opening or passage 52 therein that is normally in line with the passages 45 and 47 20 of the stationary members 44 and 46. Said stationary members 44 and 46 are connected on their outer peripheries by springs 53, which yieldingly press the contacting surfaces of said members and said disks 50 and 25 51 into close engagement so as to prevent the leakage of air past said surfaces. The members 44 and 46 are anchored by means of suitable connections 54 to the fixed framework, so that these members are held stationary in respect to the constantly rotating 30 disk 50.

The disk 50, shown in Fig. 5 has an elongated passage or opening 55 therefore, which is adapted for periodic registration with the 35 correspondingly located passages 45 and 52 of member 44 and disk 51, respectively. Assuming that the opening or passage 52 is in the position shown in Fig. 4, this registration of the passage 55, above referred to, will 40 establish communication between the passages 45 and 47, and consequently the suction created by the exhausting mechanism will be exerted at the ends of the tubes 31. This registration occurs when the tubes 31 are in 45 the dotted line position of Fig. 1, so that the lowermost article of the stack 26 is acted upon by said suction, which is of sufficient force to withdraw said lowermost article on the return movement of the tubes 31 to their 50 full line position, Fig. 1. After the passage 55 has travelled out of registration with the passages 45 and 52, by the continued rotation of disk 50, the suction exerted by the exhausting mechanism is cut off, but obviously 55 a vacuum or partial vacuum is maintained in the tubes 31 and connected parts, since the blank wall of the disk 50 is against the open end of passage 45. Thereafter, coincident with the arrival of the seized article in a 60 horizontal position on the feed table 29, a recess 56 of disk 50 moves into registration with the inner end of passage 45. This recess 56 has a passage 57 leading therefrom to the periphery of disk 50 and opening to the 65 atmosphere. Consequently, when the recess

56 registers with the inner end of passage 45, the suction in the tubes 31 is relieved by the inrush of atmospheric air through the passage 57, thus releasing the article from the suction tubes 31. In the normal operation of the machine therefore, the continuous rotation of the disk 50 procures the exertion of a vacuum through the tubes 31 to seize an article from the stack 26, and furthermore this suction is maintained to hold the article 70 against displacement until it is deposited upon the feed table 29; thereupon the suction is relieved and the article completely freed from the influence of the tubes 31, due to the inrush of air through the passage 57 75 and recess 56.

As deposited on the feed table 29, the envelope or other article is held in squared and accurate position between a pair of side guides 58, one of which is provided with a 80 light spring 59, operative against the edge of the article to press its opposite edge into contact with the opposite side guide 58. In this position the article is operated upon by a plurality of pusher fingers 60 which are 85 adapted to engage its rear edge and project it into the space between the feed rollers 15, 15. The pusher fingers 60 are carried on the end of a plate 61 which is attached to a reciprocating member 62, the latter being 90 moved back and forth horizontally in suitable guides 63, in timed relation to the other instrumentalities of the machine. Said member 62 is reciprocated in any well known manner, as for instance by a crank 100 connection with the shaft of impression cylinder 2, not shown, or in any other well known manner. The pusher fingers 60 move forward to project each article, as deposited on the feed table 29, into the space between 105 the rolls 15, whereupon said article is seized by said rolls and forwarded in the usual manner to the printing cylinders 1 and 2; said pusher fingers are then moved rearwardly, out of the way of the suction tubes 110 31, so as to provide for the delivery of the next succeeding article on the feed table 29, in position to be operated upon by the next stroke of said pusher fingers.

The disk 51 whose passage 52 has been 115 assumed to be in registration with the passages 45 and 47, is held in this position by means of a spring 65, the force of which is exerted to maintain a lug 66 on said disk in contact with a fixed pin 67. On the opposite portion of said disk from the lug 66 is provided a lug 68, from which projects a pin 69. The impression cylinder controlling shaft 8 has a depending arm 70, to the lower end of which is pivotally connected a link 120 71, having at its free end a hook 72 adapted to cooperate with the pin 69 of lug 68. A rock shaft 73 extending transversely of the machine has secured at one end, adjacent the handle 10 of shaft 8, a handle or crank 130

74. Said rock shaft 73 carries an arm 75 which in its normal position lies just beneath the hooked link 71, being held in this position by a spring 76. A spring 77, secured to 5 the link 71, yieldingly draws said link downwardly.

As heretofore stated, the depression of handle 10 on shaft 8, to cause the engagement of shoulder 11 with the arm 13, 10 procures the elevation of impression cylinder 2 into its operative position. Normally the shaft 8 remains in this latched position as long as the feed of stock between the rolls 15, 15 is continued, it being clear, as stated 15 above, that the feeler-lever 19 is prevented from rising by the presence of stock between said rolls. However, in the absence of an article between said rolls, due to a failure of the feed or to any other cause, the shaft 8 is 20 released, as above described, so as to permit its rocking by springs 9, to lower the impression cylinder 2. This rocking of shaft 8, which is availed of to separate the printing cylinders, and also to throw out the 25 clutch of the machine, in the event of a failure in the feed, is also made operative on the suction controlling instrumentalities described above. Through arm 70 and hooked link 71, the rocking of shaft 8 is communicated to the disk 51, to turn the latter a sufficient distance to carry the passage 52 out 30 of registration with passage 47, thus closing off the suction through said passages. In all 35 machines of this class, after the power is thrown off, the high momentum carries the parts through several additional revolutions, with the result that ordinarily the feed of articles is continued, thus causing a waste of stock, since said articles pass through the 40 machine without receiving any impression from the printing cylinders. By the present improvement, however, in which the suction is immediately cut off, there is no waste of stock even though the machine continues to 45 turn over a number of revolutions after the power is shut off.

In order to start up the machine, a handle or crank 74 is rocked to bring the arm 75 against the under side of link 71, thereby 50 lifting said link sufficiently to free the pin 69 from hook 72. This allows the disk 51 to return to its normal position, under the influence of spring 65. Thereupon the handle 10 of shaft 8 is rocked, to effect the engagement of shoulder 11 with arm 13, thus 55 elevating the impression cylinder 2 to its normal position, and starting up the machine by throwing in the clutch, in the usual manner. The fact that the disk 51 has been 60 returned to its normal position by the crank 74 before rocking the handle 10, insures that the suction tubes 31 will remove the lowermost article from the stack on the first downward stroke of the arm 33. Otherwise 65 the machine might immediately be stopped.

by the failure to deliver an article between the rolls 15 following the first downward stroke of the arm 33.

It is to be noted that the present invention affords a highly efficient feeding mechanism, 70 which, as applied to the feeding of envelopes to a printing press, presents marked advantages over the feeding devices now in ordinary use. In the device of the present invention, either face of the envelope may be presented to the suction tubes, whereas in all the prior devices it is usually necessary to bring about the engagement of swinging pickers, having a considerable throw with the corners of flaps that are present on one 75 side only of the envelope. Furthermore, in all prior devices of this class a great wastage of stock is inevitable, whereas with the present invention this wastage is eliminated, and at the same time the speed of feeding is increased, and the throw of reciprocating or 80 swinging parts is reduced.

We claim:

1. In mechanism of the class described, the combination with retaining means for 90 a stack of flat flexible articles, of rotary means for engaging the edges of the lowermost article to support said stack, and means for withdrawing successive articles from the bottom of said stack by flexure of said 95 articles and the frictional rotation of said supporting means.

2. In mechanism of the class described, the combination with retaining means for 100 a stack of flat flexible articles, of rotary means for engaging the edges of the lowermost article to support said stack, and a suction device operable against the bottom 105 of said stack to withdraw successive articles therefrom by flexure of said articles and the frictional rotation of said supporting means.

3. In mechanism of the class described, the combination with retaining means for 110 a stack of flat flexible articles, of rotary means for engaging the edges of the lowermost article to support said stack, and means for withdrawing successive articles, flatwise, from the bottom of said stack by flexure of 115 said articles past said rotary engaging means, the frictional rotation of said engaging means permitting the flexure of said articles.

4. In mechanism of the class described, the combination with retaining means for 120 a stack of flat articles, of rotary means engaging the edges of the lowermost article to support said stack, means for successively withdrawing articles from said stack by flexure of said articles past said rotary engaging means by frictional rotation of the 125 latter, a support for each article so withdrawn, and means for procuring the release of each article from said withdrawing means when in the plane of said support.

5. In mechanism of the class described, 130

- the combination with retaining means for a stack of flat articles, of rotary means engaging the edges of the lowermost articles to support said stack, said engaging means comprising movable elements adapted for frictional rotation by the successive withdrawals of each lowermost article.
6. In mechanism of the class described, the combination with retaining means for a stack of flat articles, of means engaging the edges of the lowermost article to support said stack, and a suction device operable against the surface of said lowermost article to flex the same past said rotary engaging means, the frictional rotation of said supporting means permitting flexure of said article.
7. In a mechanism of the class described, the combination with a movable member for successively withdrawing articles from a stack, and a rotating shaft for operating said member, of valve means mounted on said shaft for controlling a suction in said member.
8. In a mechanism of the class described, the combination with a movable member for successively withdrawing articles from a stack, and a rotating shaft for operating said member, of a valve comprising relatively movable members mounted on said shaft for controlling a suction in the withdrawing member.
9. In a mechanism of the class described, the combination with a movable member for successively withdrawing articles from a stack, and a rotating shaft for operating said member, of a valve comprising relatively movable members mounted on said shaft, the said valve members being provided with registering ports for procuring a suction in said withdrawing member in advance of each withdrawal and for procuring the release of said suction in advance of each delivery.
10. In a machine of the class described, the combination with article feeding means, a rotating shaft for operating said feeding means, and a throw-off mechanism for disconnecting said machine from the driving power, of valve means mounted on said
- shaft and operated by the rotation thereof for controlling a suction in said feeding means, and means coacting with said valve means for immediately shutting off the suction from said article feeding means upon the operation of said throw-off mechanism.
11. In a machine of the class described, the combination with article feeding means, a rotating shaft for operating said feeding means, and a throw-off mechanism for disconnecting said machine from the driving power, of a valve mounted on said shaft and operated by the rotation thereof for controlling a suction in said feeding means, and means for shutting off the valve from the suction upon the operation of said throw-off mechanism to prevent further operation of said article feeding means upon continued rotation of said shaft.
12. In a machine of the class described, the combination with article feeding means, a rotating shaft for operating said feeding means and a throw-off mechanism for disconnecting said machine from the driving power, of a valve comprising relatively movable members one of which is rotatable with said shaft for controlling a suction in said feeding means, and means for moving another of said valve members upon the operation of said throw-off mechanism to shut off the suction.
13. The combination, with the feed devices and throw-off mechanism of a printing press, of a suction member normally operative to deliver articles to said feed devices, rotary means driven simultaneously with said feed devices for controlling the suction through said member, and means cooperating with said rotary means for shutting off the suction through said member in response to the actuation of said throw-off mechanism and the disk connection of the press from the driving power.

Dated this fifth day of December, 1918.
